FIG. 2

FIG. 3

FIG. 1 is a front perspective view of the television antenna, showing my new design;

FIG. 2 is a top plan view thereof;

FIG. 3 is a right side elevational view thereof, the left side elevational view being a mirror-image;

FIG. 4 is a top plan view of a second embodiment of the television antenna;

FIG. 5 is a front elevational view of said second embodiment;

FIG. 6 is a left side elevational view of said second embodiment, the antenna ears illustrated in FIGS. 4-6 being foreshortened to enable the body thereof to be enlarged for the purpose of the drawings; and

FIG. 7 is a front elevational view of the television antenna in the form of FIGS. 1-3, with the central antenna ear being shortened.

I claim:

The ornamental design for television antenna, as shown and described.
